UNITED STATES PATENT OFFICE.

FRIEDRICH CORRELL, OF MANNHEIM, GERMANY.

COIN-PAYING-OUT MACHINE.

1,160,580.

Specification of Letters Patent. Patented Nov. 16, 1915.

Application filed December 29, 1913. Serial No. 809,201.

To all whom it may concern:

Be it known that I, FRIEDRICH CORRELL, a subject of the German Emperor, and resident of Werderstrasse 14, Mannheim, Germany, have invented new and useful Improvements in Coin-Paying-Out Machines, of which the following is a specification.

The present invention relates to an improvement in coin paying out machines, in which the coins are singly ejected as in the paying out devices described in the German specifications 195,911 and 212,189 by means of ejectors arranged in the paying slab.

The object of the present invention is to provide means to eject singly coins which have been substituted for a coin of particular denomination and of which the supply has become exhausted or depleted.

With the machines as heretofore constructed, when the coins of one denomination became exhausted the paying out of the desired amount was effected in a different coin either by the coin ejectors or the coin tubes being vertically displaced, so that say instead of a fifty pfennig piece successively five ten pfennig pieces were paid out; or the slide for the coins which have been exhausted was disengaged, and a substitute slide belonging to a substitute coin holder was engaged. The former arrangement had the disadvantage, that owing to the different thicknesses of the coins in use the paying out became unreliable; the other method was very complicated for reason of the necessary provision of substitute slides.

According to the present invention the paying out point of the respective kind of coin remains the same, only there is substituted for the coin itself a different one of a lower value, and at the same time the number of the ejectors operated by the movement of the paying plate is multiplied by the respective factor. If, for instance, the fifty pfennig pieces have run out, the respective coin tube is filled with ten pfennig pieces, or the tube is exchanged for one filled with ten pfennig pieces, whereas the paying out mechanism is so adjusted, that at each paying out operation not one but five ejectors are successively operated.

It is obvious that the present invention chiefly relates to machines as disclosed in the United States Patents No. 897,082, to Gauss, Aug. 25, 1908, and No. 943,030, to Menchen, Dec. 14, 1909.

The essential feature of the present in-

vention consists in that besides the normally employed coin ejectors a number of additional ejectors is provided, which may be optionally operated from the members operating the ejectors by either engaging or disengaging them.

In the accompanying drawing the present invention is exemplified in several constructional forms.

Figure 1 is a section on the line A—B through Fig. 2 showing the paying out plate of a paying out machine, the 3-mark slide being shown in the position in which it pays out a 3-mark piece when the machine is operated. Fig. 2 is a plan view partly in section. Fig. 3 is a section on the line C—D in Fig. 2. Fig. 4 is the same section at a position in which the 3-mark slide pays out 3 single mark pieces when the machine is operated. Fig. 5 is a section on the line E—F in Fig. 2. Fig. 6 is a section similar to that shown in Fig. 1 showing the 2-pfennig slide. Figs. 7 and 8 are other constructional forms of the paying plate. Fig. 9 is a top view of Fig. 8, the cover plate having been partly omitted. Fig. 10 is another constructional form of the adjusting member for the additional ejectors. Fig. 11 is again another constructional form of the paying out plate. Fig. 12 is a section on the line G—H and Fig. 13 is a section on the line J—K in Fig. 11. Fig. 14—16 also show a further constructional form of the paying out plate.

The paying out plate 1 is moved in known manner by means of a crank 2 beneath the stationary coin tubes 3. At the one end of this plate are adjusting plates 4, having recesses of various depths, which adjusting plates can be so moved or adjusted by means of keys or slides, that the bar 5 will, on a bolt 6 being released advance to a more or less long distance and thereby lift more or less coin ejectors above the surface of the paying out plate.

In the constructional form according to Figs. 1 and 2 it has been assumed, that the coin container 3 for paying out the 3-mark pieces comes into question. The rod 5 of this container has one single cam 8 only. Besides there is, as heretofore only one single ejector 7 pivotally fitted at 9 in the transverse wall 1' of the paying out plate 1. This ejector is beveled at its lower end, so that it will be raised by the cam 8 when the rod 5 is advanced.

According to the present invention the arrangement is such, that at the transverse wall 1' and in the same level with the ejector 7 two further ejectors 7' are provided. The rod 5 furthermore has two guide pins 10, on which two cams 8' having U-shaped straps 11 can be displaced. The strap 11 engages through cam slots of two disks 12 (Figs. 3, 4), which are fitted to a shaft 13, and may be turned by a key 14 loosely fitted to said shaft. By such means the cams 8' are drawn forward or back on their guide pins, and held in their terminal position by a spring 15 acting on the shaft 13 (Fig. 5).

As will be evident from the drawing the cams 8' are, at the position of the strap 11 shown in Fig. 4, in the path of the ejector 7, so that when the rod 5 is advanced not only the ejector 7 is operated by cam 8, but also the ejectors 7'. It is obvious that in this case a 1-mark tube must have been substituted for the 3-mark tube, before the auxiliary cams 8' are engaged.

When 3-mark pieces shall again be paid out, the 3-mark tube is fitted again and by turning the shaft 13 by aid of key 14 the strap 11 is moved back into the position shown in Fig. 3, so that the cams 8' are moved from the path of the ejectors 7' and only the ejector 7 is raised. The auxiliary cams 8' may, of course, also be fitted rigidly to the rod 5, if the auxiliary ejector 7' is so arranged, that it can be moved from the path of said cams.

In Fig. 6, the mechanism shown is arranged for use with the 2-pfennig tube and the conditions are such that the additional ejectors 7' coincide exactly with the other ejectors as regards their distance from the respective cams, so that when the rod 5 engages in the first step of the adjusting plate 4 or after the two cams 8' have been engaged, the ejector 7 and the first ejector 7' are raised. When the rod 5 engages in the second step only the two other cams 8, 8' come into action, so that then four ejectors project above the paying out plate.

Fig. 7 illustrates another constructional form of the paying out plate. Whereas in the foregoing exemplifications the ejectors 7, 7' remain stationary and the cams 8, 8' advance with the rod 5, here the reverse arrangement is provided. The ejectors 7, 7' are pivotally fitted to the slide 5, and the cams 8, 8' are secured to the transverse wall 1'. The cam 8' is also here arranged to be engaged and disengaged by aid of a strap 11 and a cam disk 12.

Fig. 8 illustrates a constructional form in which the ejectors 7 are guided vertically in the paying out plate, and are controlled by means of two pins provided at the side in cam grooves of the slide 5. The additional ejectors 7' are vertically adjustable in the rod 5 and project below beyond the paying

out plate, where they are beveled at their ends. The cams 8' are fitted to a displaceable rod 16 which can be fixed by aid of notches. The operation of this arrangement is such, that when the slide 5 engages in the notch in the adjusting plate 4, the ejectors 7 are raised by the cam slots in slide 5, and the ejectors 7' by the cams 8', accordingly as the rod 16 is displaced more or less far so that the cams 8' come into the range of the ejectors 7'. In place of the draw-out rod 16 also a revoluble shaft 17 may be employed as shown in Fig. 10. On this shaft are fitted in several rows behind and beside each other a given number of cams 8', which can be turned from outside preferably after an index 18 into the path of the ejectors 7'.

In Fig. 11 a constructional form is shown, in which the ejectors are revoluble. The ejectors 7 are suspended on small brackets 85 on the top plate of the paying out plate, and are controlled by means of pins in cam slots in the rod 5. The additional ejectors 7' are likewise revoluble, but are fitted in the rod 5 and have a downward projecting arm 20. 90 A shaft 17 with a cam 8' is fitted beneath the paying out plate. The operation of this constructional form is the same as that of the last constructional form.

The constructional form of the paying out plate according to Figs. 14 and 15 is such that the ejectors are not raised above the surface of the paying out plate but rock out sidewise and when not in use, move between the coin tubes 3. In this case the ejectors consist of a bolt 21 pivotally fitted in the top plate, having at the top an arm 22 and below an arm 23. To the arm 22 is fitted the ejector 7 proper and 7', which projects upward through a slot in the plate and is generally held by a spring in the position shown in Fig. 14.

The rod 5 is provided with noses 8 which, on the rod 5 advancing, engage against the lower arms 23 of the ejectors 7 and thereby rock these. To the slide 5 is further fitted a shaft 17 revolving in bearings 24. This shaft is likewise fitted with noses 8' which abut against the arms 23 of the ejectors 7' and rock them, according to the position to which the shaft is set.

In all hereinbefore described constructional forms the cams or abutments 8, 8' are displaceable, that is to say, engageable and disengageable. In Fig. 16 a constructional form of the paying out plate is shown in which all cams are fixed, and the additional ejectors 7' are engageable and disengageable. The ejectors 7' are displaceable on their axis 9 by means of a strap 11, the ends of which engage in slots in the ejector and can be engaged and disengaged into the path of the cams 8' in the same manner as in Fig. 1 by means of cam disks.

It is obvious that the present invention

can also be carried out in several other constructional forms.

I claim:

1. In a coin-paying out machine including suitable containers and a movable paying out plate to coöperate therewith: coin ejecting members adapted to remove a coin from a selected container; and normally inoperative auxiliary ejecting members for the respective containers, and means to render the same operative with their respective first-named ejectors, the said auxiliary ejectors for a respective container being one fewer in number than the required coins of lower denominations for the same value, whereby it is possible when said auxiliary ejectors are rendered operative to substitute and to pay out for the coin originally and normally paid out, should the latter become exhausted or depleted, coins of lower denomination.

2. In a coin-paying out machine including suitable coin containers and a movable paying out plate to coöperate therewith: coin ejecting members adapted to remove a coin from a selected container; and normally inoperative auxiliary ejecting members for the respective containers and including two members, one of which is displaceable relatively to the other, and means to adjust the displaceable member to effect an engagement between the two said members and render the auxiliary ejecting means operative, the said auxiliary ejectors for a respective container being one fewer in number than the required coins of lower denomination for the same value, whereby it is possible when said auxiliary ejectors are rendered operative to substitute and to pay out for the coin originally and normally paid out, should the latter become exhausted or depleted, coins of lower denomination.

3. In a coin-paying out machine including suitable coin containers and a movable paying out plate to coöperate therewith: coin ejecting members adapted to remove a coin from a selected container, and movable means to set said ejecting members; normally inoperative auxiliary ejecting members for the respective containers, and means carried by said ejector setting means to bring the auxiliary ejecting members into operative position, the latter being normally displaced from the former, and means to bring the one into the path of movement of the other, the said auxiliary ejectors for a respective container being one fewer in number than the required coins of lower denomination for the same value, whereby it is possible when said auxiliary ejectors are rendered operative to substitute and to pay out for the coin originally and normally

paid out, should the latter become exhausted or depleted, coins of lower denomination.

4. In a coin-paying out machine including suitable coin containers and a movable paying out plate to coöperate therewith: coin ejecting members adapted to remove a coin from a selected container; normally inoperative auxiliary ejecting members for the respective containers; rotatable rods therefor, and means thereon adapted to engage said auxiliary ejectors to render the same operative.

5. In a coin-paying out machine including suitable coin containers and a movable paying out plate to coöperate therewith: coin ejecting members adapted to remove a coin from a selected container; and normally inoperative auxiliary ejecting members for the respective containers, means to render the same operative with their respective first-named ejectors, the said auxiliary ejectors for a respective container being one fewer in number than the required coins of lower denomination for the same value, whereby it is possible when said auxiliary ejectors are rendered operative to substitute and to pay out for the coin originally and normally paid out, should the latter become exhausted or depleted, coins of lower denomination, and indicating means connected therewith.

6. In a coin-paying out machine including exchangeable coin containers and a movable paying out plate to coöperate therewith: coin ejecting members adapted to remove a coin from a selected container; normally inoperative auxiliary ejecting members for the respective containers; rotatable rods therefor, means thereon adapted for engagement with said auxiliary ejectors to render the same operative; and indicating means connected with said rods.

7. In a coin-paying out machine including exchangeable coin containers and a movable paying out plate to coöperate therewith: coin ejecting members adapted to remove a coin from a selected container; normally inoperative auxiliary ejecting members for the respective containers; rotatable rods therefor, and a plurality of cams arranged in several rows and in predetermined order upon said rods and adapted for engagement with the respective auxiliary ejecting members upon rotation of the said rods.

In testimony, that I claim the foregoing as my invention, I have signed my name in presence of two witnesses, this 12th day of December 1913.

FRIEDRICH CORRELL.
